Primary Examiner — Darlington Ly*Assistant Examiner* — Daniel J Domino(74) *Attorney, Agent, or Firm* — Wolf, Greenfield & Sacks, P.C.(57) **CLAIM**

The ornamental design for a display screen with icon, as shown and described.

DESCRIPTION

The sole FIGURE is a front view of the display screen with icon showing our new design.

The broken lines showing a device illustrate environment, whereas the broken lines showing a display screen illustrate portions of the article. None of the broken lines form part of the claimed design.
